UNITED STATES PATENT OFFICE.

EDWARD J. DAILEY, JR., OF NEW YORK, N. Y., ASSIGNOR TO GRAYBAR ELECTRIC COMPANY, INC., OF NEW YORK, N. Y., A CORPORATION OF NEW YORK.

LIGHTING FIXTURE.

Application filed September 21, 1925. Serial No. 57,510.

Illuminating systems and devices are designed in a manner to prevent objectionable glare. No matter what precautions have been taken, it has been difficult to eliminate 5 all of the glare and yet provide sufficient uniform illumination for the desired area.

The object of the present invention is to control the intensity of illumination without producing a corresponding glare within 10 the angle of vision.

Another object of the invention is to provide means for re-directing some of the light of an enclosed direct or semi-direct lighting unit from the lower to the upper hemisphere of the lighting unit.

A still further object of this invention is to provide a simple compact and efficient adjusting means to control the illumination within the angle of vision which is universally adaptable to enclosed lighting units of existing types.

Reference is now had to the drawings forming a part of this specification, in which:

25 Figure 1 is an elevation of one form of the invention as applied to a fixture wherein the shield is either translucent or transparent.

Figure 2 is a similar view showing an 30 opaque shield.

Figure 3 is a similar view showing an opaque shield with lower apertures to permit partial direct illumination.

Figure 4 is a view partially in section, 35 showing the adjusting means hereinafter described.

In the drawings *a* represents a suitable globe adapted to be secured to the support *b* by means of screws *c* in a well known manner. Within the support is provided a bulb *d* whose filament or center of light source is at *e*.

A shield *f*, Figure 1, is provided and it 45 may be of translucent material. This shield is adjustably secured to the globe *a* by means of a threaded stem *g* on which are provided nuts *h* and washers *i* for clamping the shield therebetween, as clearly shown in Figure 4. The lower end of the stem may have an internally and externally threaded collar *j*,

the body of which extends below the globe *a* to enable the stem to be adjusted when the globe is mounted on the support.

A slot *n* is provided in the lower end of the stem *g* and provides an easy means of 55 adjusting the shield. By removing the cap *k* and inserting a screw driver in the slot, the shield may be raised or lowered at will, thus converting the unit from a direct to an indirect one, or varying the light given 60 off at angles, known as the angles of vision.

A lock nut *o* of suitable design is provided to screw over the collar and secure globe *a* between the flange and nut. An ornamental nut *k* with ample room left 65 within for adjusting the stem *g* to any desired position may be used to give a finished appearance. Washers may also be provided to protect the globe.

In Figure 2 the shield *f'* is of opaque 70 material, thus providing for purely indirect lighting as distinguished from Figure 1, wherein both direct and semi-direct lighting is had.

In Figure 3 the shield *f''* is of opaque material and provided with lower apertures as at *m* whereby some of the light is allowed to pass through to afford direct illumination and some of the light is reflected for indirect lighting, as in Figures 1 and 2. 80

It will be appreciated that the shields may be adjusted by means of the stem *g* and collar *j*, while the fixture is in illuminating position, thus adding greatly to the convenience of the device and its use where 85 it is desired to effect a change in the illumination of the surrounding area.

It is to be understood that applicant is not limited to the specific form of deflector or shield shown, since this does not 90 form a material part of the invention, but merely serves to redirect the light striking it, to the upper hemisphere of the globe and ceiling from which it is reflected in the usual manner, thus enabling the unit to 95 be converted from a direct, into a semi-direct or totally indirect lighting unit.

With this adjustable deflector attached to enclosed direct lighting units, there is obtained the effect of a semi-direct lighting 100

unit when lighted, and the appearance of a compact, presentable and neat, enclosed lighting unit, whether lighted or unlighted.

What I claim is:

6. In a lighting fixture, a globe, a movable threaded stem extending through the bottom of the globe, a light deflector rigidly

mounted on the stem and within the globe, and means on the lower part of the stem and outside of the globe for adjusting the 10 position of said deflector.

This specification signed this 17th day of September, A. D. 1925.

EDWARD J. DAILEY, JR.
